UNITED STATES PATENT OFFICE.

WILLIAM NATHAN GILBERT, OF DAYTON, OHIO, ASSIGNOR TO INTERNATIONAL SCALE COMPANY, OF DAYTON, OHIO, A CORPORATION OF ILLINOIS.

PENDULUM SCALE.

Application filed July 13, 1920. Serial No. 395,900.

To all whom it may concern:

Be it known that I, WILLIAM NATHAN GILBERT, a citizen of the United States of America, residing at Dayton, in the county 5 of Montgomery and State of Ohio, have invented certain new and useful Improvements in Pendulum Scales, of which the following is a full, clear, and exact description.

This invention relates to certain improvements in scales, and more particularly to 10 scales of the class having a pivotal indicator, pendulum counterbalancing means, an operating connection between the counterbalancing means and the indicator and an intermediate lever intermediate the pendulum and the load to be counterbalanced.

Certain of the objects of the present invention reside in the provision of an exceeding 15 compact scale of the above type, which will be simple to manufacture, adjust and seal, and one which will maintain accuracy after long periods of use.

Other objects reside in the provision of 20 certain adjustment devices whereby the pendulum and indicating devices may be readily set to work with accuracy under varying conditions.

Another object resides in the provision 25 of a novel form of driving connection between the indicator and the pendulum load counterbalanceing means. The connection is of such a character that it may readily be adjusted to provide proper depth of enmeshment between the rack and pinion and 30 proper enmeshment pressure between the same elements. The connection is also adapted to prevent damaging shocks being imparted to the indicating system when sudden loads are applied to the scale.

40 Other particular objects and advantages will be more fully pointed out in the accompanying specification and shown upon the drawings, in which:

Fig. 1 shows a front elevation of my improved scale.

Fig. 2 shows a sectional side view of the scale.

The scale operating parts are preferably housed in a dial housing 10 and beam housing 11. The latter is provided with suitable brackets 12 to support the bearings which receive and support knife edges 13. These knife edges are carried by and form the fulcrum for an intermediate lever 14 of the 55 third order. This lever may carry a tare

beam 15 which is supported outside the housing by suitable studs which project through slots in the housing wall.

Beam 14 also carries knife edges 16 which support a loop bearing carried by a steel- 60 yard 17 leading to the goods support or base lever system (not shown). The beam 14 likewise carries knife edge pivots 18 which coact with a loop bearing 19 having means for clamping thereto a pair of flexible tapes 20.

Bolted to the dial housing is a frame 21 which is provided with suitable bearings 22 for mounting the main pendulum carrying arms 23. Also fastened to frame 21 is 70 a depending forked frame 24 carrying pointed pins 25 which support pairs of coacting overlapping rollers 26 and 27. The edges of the rollers 26 and 27 are beveled and support an arbor 28 carrying a pinion 29. These 75 rollers form a disc bearing support for the pinion arbor and allow the same to rotate with a minimum of friction. Carried upon the end of the arbor 28 is a counterbalanced pivotal indicator 30 which sweeps over a 80 dial 30^a carried by the dial housing. To prevent endwise movement of arbor 28, it is preferably shouldered and this shouldered portion is adapted to abut against the discs—should the arbor move excessively 85 endwise.

Pivoted fastened upon the main arms 23 are secondary arms 31 which are threaded to receive pendulum weights 32. These weights are adjustable vertically relative to 90 the secondary arms 31 and after they are shifted to the desired vertical adjustment, they may be locked by means of set screws 33.

I also provide means for adjusting the 95 pendulum horizontally or angularly relative to the main arms 23. This adjustment is secured to give-and-take screws 34 which are carried by brackets 35 supported on the lower ends of the main arms 23. By adjusting the screws 34 in and out their ends will contact with the secondary pendulum weight arm 31 and thereby the weight arms and the pendulum thereon can be adjusted and locked at any desired relative horizontal 100 or angular position.

Pivoted upon the upper ends of the main arms 23 are adjustable compensating cams 36 to which are fastened the tapes 20.

Upon one of the main arms 23 is a block 110

37 which is so fastened to the arm as to be slidably adjustable relative thereto. To this block is secured spring 38 preferably of the blade type and U-shaped and carrying upon its opposite end a forked member 39 carrying a pivot for a horizontally-extending downwardly-facing rack 40.

This rack meshes with the pinion upon the arbor shaft and thereby imparts displacement to the pointer 30 in accordance with the displacement of the pendulum load-counterbalancing means. Should a load be suddenly placed upon the scale the spring 38 acts as a shock-absorber and prevents the shock of impact being suddenly imparted to the indicating system.

In order to secure the proper light yielding pressure between the rack 40 and the pinion 29 a spring 41 is utilized. This spring (here shown as a continuation of spring 38) is preferably of U-shape and bears against a set screw 42 carried by the rack. By adjusting this set screw and vertically shifting the position of spring 38 the depth of enmeshment of the rack may be changed. Thereafter the enmeshment pressure between the rack and pinion may be varied by further adjustment of set screw 41. In order to prevent the rack from jumping out of mesh a forked blade 43 is provided which extends over and is slightly spaced from the rack as shown in Fig. 2.

To bring the scale to proper zero balance a suitable adjusting poise 44 may be utilized. This poise is carried upon a threaded shaft which is supported by the main scale beam 14. Oscillations of the beam are damped by means of a dash-pot 46.

In order to secure access to the pendulum and indicator assembly for adjustment, the dial housing is provided with a removable closure 47. The beam housing likewise is provided with a removable closure 48.

The operation of the improved scale will be readily understood. A downward pull upon the draft rod rocks lever 14 about its fulcrum thereby drawing down tapes 20. These tapes then pull downwardly upon the pendulum arms and elevate the weighted arms proportionally to the load thereon. The rack 40 is then drawn to the left and rotates the pivotal indicator shaft to indicate on the dial the amount of the counterbalanced load.

Having described a preferred embodiment of my invention what I desire to claim is more particularly pointed out in the appended claims.

I claim:

1. In a weighing scale, in combination, a pivotal indicator, an arbor therefor, a pinion carried thereby, a pendulum load counterbalancing means, means for displacing the pivotal indicator in accordance with the displacement of the pendulum load counter-

balancing means, said means comprising a spring coupled to the pendulum means, and a horizontally-extending rack coupled to said spring and engaging the aforesaid pinion, said spring serving as a shock-absorber 70 when sudden loads are applied to the scale.

2. In a weighing scale, in combination, a pivotal indicator, an arbor therefor, a pinion carried thereby, a pendulum load counterbalancing means, means for displacing the indicator proportionally to the displacement of the load counterbalancing means, said means comprising a spring connected to the pendulum means, a horizontally-extending rack pivotally supported by said spring, said rack engaging the aforesaid pinion, and a tension device comprising a spring carried by the first mentioned spring, and a set screw carried by the rack and engaging the second mentioned spring member for the purpose described. 80

3. In a weighing scale, in combination, a pendulum load counterbalancing means, a member adjustable vertically thereon, a spring carried by said member, a horizontally extending rack coupled to said spring, a pinion engaged by said rack and an arbor and a pivotal indicator turned thereby upon the lateral displacement of the rack, said adjustable support for said spring permitting the rack to be elevated or depressed relatively to the pinion. 90

4. In a weighing scale, in combination, a pendulum load-counterbalancing means including a supporting arm for a pendulum weight, a shock-absorbing spring carried by and adjustable vertically relative to said arm, a horizontally-extending rack coupled to said spring, a pinion engaged thereby, a pivotal indicator connected with said pinion, and an adjustable tension spring coacting with said rack, said spring last mentioned and the shock absorbing spring being adapted by adjustment thereof to control the depth of enmeshment of the rack and pinion and the enmeshment pressure therebetween. 105

5. In a weighing scale, in combination, a pendulum load counter-balancing means, a U-shaped shock-absorbing spring carried thereby, a block carried upon the end of said spring, a pintle support supported thereby, a horizontally-extending rack pivotally supported upon the said pintle, a pinion engaged by the rack and connected with a pivotal indicator, a blade spring carried by the aforesaid block and overlying the rack, and adjusting means carried by the rack coacting with said blade spring to vary the enmeshment pressure between the rack and pinion. 115

6. In a weighing scale, in combination, a scale beam, a draft rod connected thereto, a pair of pendulum load-counterbalancing devices, each device comprising a 120

compensating cam, a main arm, a secondary arm pivotally supported by the main arm and angularly adjustable relatively thereto, and a weight carried by the secondary 5 arm, and flexible tapes connecting the said compensating cams with the scale beam.

7. In a weighing scale, in combination, a scale beam, a draft rod connected thereto, a pair of pendulum load-counterbalancing 10 devices, bearings therefor disposed above the beam, each said device comprising a main pendulum arm, a compensating cam carried thereby and adjustable relatively thereto, a secondary arm pivotally supported 15 on the main arm and adjustable angularly relatively thereto, and a pendulum weight adjustable vertically relative to the secondary arm, and flexible tapes connecting the scale beam with the compensating 20 cams which form part of the pendulum load-counterbalancing means.

8. The invention set forth in claim 6 in which a pivotal indicator and pinion is provided, and having a horizontal rack- 25 engaging the pinion and coupled with the pendulum load-counterbalancing means.

9. The invention set forth in claim 6 in which a pivotal indicator is provided to indicate the counterbalanced load and having a pinion connected with said indicator, a rack engaging the pinion and a shock-absorbing spring coupling the rack and the pendulum load-counterbalancing means. 30

10. In a weighing scale, in combination, a scale beam of the second order of leverage, a draft rod connected thereto, a pair of tapes connected to said beam, a pair of pendulums journaled above said beam and connected thereto by the aforesaid tapes, a pivotal indicator having an arbor, disc-bearing 35 supports for said arbor, and means comprising a rack and pinion for coupling said indicator with one of the aforesaid pendulums.

45 11. In a scale, in combination, a dial hous-

ing, a frame carried thereby, pendulum bearings in said frame, a pair of disc bearings carried by said frame and supporting an arbor, a pivotal indicator and a pinion thereon, a pair of pendulums carried by the 50 aforesaid bearings in said frame, a scale lever fulcrumed below the pendulum, a pair of tapes connecting the pendulum thereto, a horizontal rack meshing with the pinion, and shock-absorbing and tension-adjusting 55 springs coupling the rack with the pendulum means and controlling the enmeshment pressure between the rack and pinion.

12. A weighing scale including in combination, a pivotal indicator, pendulum load counterbalancing means comprising a pair of pendulums, means for operating said pendulum load counterbalancing means in accordance with applied loads, and driving means for said pivotal indicator connected 60 to the pendulum means, said driving means including a yielding shock absorbing connecting device having provisions adapted to permit the yielding of said driving connection in either direction upon the application 65 of shock to the parts.

13. In a weighing scale, in combination, a pivotal indicator, a scale beam, a pair of pendulum load counterbalancing devices, each device comprising a main arm, a secondary arm pivotally supported upon the main arm and angularly adjustable relatively thereto, a weight carried by the secondary arm, means connecting the pendulum devices with the beam, and driving devices for the pivotal indicator operated directly by and from said pendulum devices, said driving devices including a yielding blade-like spring operatively connected to the pendulum devices and adapted to yield 75 in either direction upon the application of shocks to the parts.

In testimony whereof I hereto affix my signature.

WILLIAM NATHAN GILBERT.
